UNITED STATES PATENT OFFICE.

HENRY G. LEWIS AND WALTER S. MAYER, OF PHILADELPHIA, PENNSYLVANIA,
ASSIGNORS TO ELECTRIC SERVICE SUPPLIES COMPANY, OF PHILADELPHIA,
PENNSYLVANIA, A CORPORATION OF PENNSYLVANIA.

CONTACT-SHOE.

1,378,695.

Specification of Letters Patent. Patented May 17, 1921.

Application filed November 20, 1918. Serial No. 263,259.

To all whom it may concern:

Be it known that we, HENRY G. LEWIS and WALTER S. MAYER, citizens of the United States, and residents of the city of Philadelphia, in the county of Philadelphia and State of Pennsylvania, have jointly invented certain Improvements in Contact-Shoes, of which the following is a specification.

This invention is an improved contact shoe 10 designed especially for taking current from a contact rail in the operation of electric cars, cranes, conveyers and other electrically operating traveling devices. It comprises means whereby the shoe is adapted to be reversed 15 so that it can be used for making either top or bottom running contact, means whereby the contact member is adapted to be reversed by turning it in its own plane or about either of transverse axes to effect a desired distribution 20 of wear, means whereby the contact member is permitted a limited universal play to effect a desired accommodation to the rail, and means whereby the contact member is adapted for ready connection with conductors for carrying the current. The contact 25 may, however, be made an integral part of the oscillatory arm.

A leading purpose of our improvements is to provide a contact shoe of simple, substantial and efficient character adapted for automatic as well as manual adjustment to varying conditions of use, whether in the operation of cars or otherwise.

The characteristic features and advantages 35 of our improved shoe will be more fully understood from the following description of types thereof and the accompanying drawings illustrating same.

In the drawings, Figure 1 is a top plan view of a shoe made in accordance with our invention; Fig. 2 is a side view of the same applied to a support shown in section; Fig. 3 is a front elevation of said shoe; Fig. 4 is a top plan view of a modified construction; Fig. 5 is a side elevation of the construction shown in Fig. 4 applied to a support shown in section; Fig. 6 is a sectional view taken on the line 6—6 of Fig. 1 in illustration of features common to both types of the device; Fig. 7 is a sectional plan view of a further modified construction taken on the line 7—7 of Fig. 8; and Fig. 8 is a sectional elevation taken on the line 8—8 of Fig. 7.

The improved shoe comprises the bracket

1 adapted to be clamped to a support 2 such as a car sill, the bracket being adjustable to and held in different vertical positions by means of the slots 3 for passage of bolts 4 carried by the support and the serrated sections 5 for engagement with serrated blocks 6 clamped thereto by the nuts 7 on the bolts. The bracket is provided further with the cylindrical bearings 8 on opposite sides of its lower part, and with the housing 9 providing seats 10 and 11 containing the respective slots 12 and 13, disposed between the bearings. A block 14 containing sockets 15 and 16 is clamped by the bolts 17 to the bracket above the housing 9.

In the form of the invention illustrated in Figs. 1 to 3 inclusive, a rocker arm 18 is provided with the integrally formed bearings 19 and the detachable bearings 20 clamped together by the bolts 21 around the bearings 8 in rocking relation thereto, the rocker arm being provided with the further bearings 22 having the fins 23 thereon.

A contact member 24 is engaged between the bearings 22 by a pin 25 passing therethrough, the pin being of such smaller diameter than the member's central bore 26 and larger end bores 27 as to permit such member substantial play universally with relation to such pin. The contact member 24 is provided with the corner recesses 29 of increasing depth as they approach the respective edges of the member, with the recesses 30 between the respective pairs of recesses 29, with sockets 31 between contiguous recesses 29 and 30, and with threaded holes 32 adapted for receiving binding screws 33, providing a comparatively light as well as strong structure having convenient means in its several reversed positions for electrical connection with the block 14 through the wires 34.

The fins 23 extend into adjacent recesses 29 to limit the action of the member 24, which is permitted thereby a limited rocking movement on the pin 25 and limited rocking movements transversely thereto, for accommodation to the surface of the rail, the member being reversible to distribute the wear (when the pin is removed and the wires detached) by turning such member in its own plane or upside down either around its axis or transverse thereto.

In the form illustrated in Figs. 4 and 5,

the modified rocker arm 18', which is engaged to the bearings 8 as previously described, is provided with a bearing 22' which extends into the recess or through passage 30' 5 of the contact member 24'; this member being provided with the corner recesses 29', the sockets 31' for the wires 34, and the bores 27' for the passage of a pin 25' which extends through the larger bore 26' in the bearing 22'. The member 24' is permitted 10 a limited universal oscillation, on its axis and transversely thereto, by its free connection with the part 18'; and can be reversed; the automatic movement to effect accommodation due to irregularities in the rail or the 15 swaying of the car and the reversal to effect distribution of wear, as described in connection with the member 24, for which it can be substituted.

20 The arms 18 and 18' are each provided with a seat or socket 35 for holding a spring 36, through which and one of the slots 12 or 13 passes a bolt 37, the bolt head engaging a washer or bearing 38 through which tension is applied to the spring and pressure is 25 applied thereby to the seat by screwing up the bolt's nut.

A substantially U-shaped guard 39 is adapted to be sprung over the parts 10 and 11, having a hole 40 in a leg thereof for the passage of the bolt 37 to hold it in place.

In the application of the spring 36 and its connected parts, as illustrated, the arms 18 and 18' to which they are applied will be 35 pressed upwardly, to press the members 24 and 24' upwardly, as required for underrunning contact. But it will be understood that by disengaging the parts 20, 37 and 39 the corresponding parts 18 and 18' can be reversed 40 in their relation to the part 1 and connected for effecting a top running contact with the member 24 and 24', the bolt 37 now extending downwardly through the slot 12 and drawing downwardly upon the spring 45 36 which acts through its seat 35 to press downwardly the corresponding arms 18 and 18'.

In the form illustrated in Figs. 7 and 8, the bracket 1 carries an integrally formed 50 arm and contact member 18'' connected in reversible relation to the bearings 8 for effecting either top or bottom contact, by the parts 19 and 20 through which pass the bolts 21 and which have ends of the conductors 34 55 clamped between them to carry current therefrom to the part 14. The part 18'', which is shown in top running relation to the rail, is pressed downwardly by the connection of the recessed bolt 37 with the reversed guard 39 and the part 10, the bolt 60 acting through the washer 38 on the spring 36 in the socket 38, reversed with relation to the position thereof previously shown.

Having described our invention, we claim:

65 1. In an electrical contact device, the com-

bination with a supporting member, of an oscillatory member connected in reversible relation thereto, a contact member carried by said oscillatory member, and mechanism comprising reversible means whereby said oscillatory member can be pressed in opposite directions. 70

2. In an electrical contact device, the combination with a supporting member provided with bearings, of an oscillatory member having bearings adapted to be clamped together around said bearings first named, a contact member connected in movable relation to said oscillatory member and mechanism comprising reversible means whereby 80 said oscillatory member can be pressed in opposite directions. 75

3. In an electrical contact device, the combination with a supporting member, of an oscillatory member connected in reversible 85 relation thereto and limited to movement on a horizontal axis, and a contact member connected in universally movable relation relative to said oscillatory member.

4. In an electrical contact device, the combination with a supporting member having bearings, of a member connected in oscillatory relation to said supporting member and having a bearing disposed between said bearings first named, means comprising a spring 95 adapted to be disposed between said bearing second named and either of said bearings first named to press said oscillatory member in either direction, and a contact member connected with said oscillatory member. 100

5. In an electrical contact device, the combination with a supporting member having oppositely disposed bearings and oppositely disposed slotted seats, of an oscillatory member mounted on said bearings, said oscillatory member having a seat connected therewith, a bolt adapted to be passed through said seat and either of said seats, a spring adapted to be placed on said bolt between said seat and either of said seats, and a contact member connected to said oscillatory member. 105

6. In an electrical contact device, the combination with a supporting member having seats, of an oscillatory member connected in reversible relation to said supporting member and having a seat, a bolt extending through said seat and adapted to pass through either of said seats, a spring on said bolt adapted to exert pressure against said seat and either of said seats, a guard engaging said seats and covering said seat and spring, and a contact member connected with said oscillatory member. 115

7. In an electrical device, the combination 125 with a supporting member, of an oscillatory member connected in reversible relation therewith, means whereby said supporting member and oscillatory member can be connected to press said oscillatory member in 130

opposite directions, and a contact member pivotedly connected in reversible relation to said oscillatory member, said oscillatory and contact members having engaging means 5 for limiting the movement of said contact member.

8. In an electrical contact device, the combination with a bracket, of reversible mechanism comprising a contact member connected in oscillatory relation to said bracket, and means for pressing said mechanism in opposite directions in its reversed positions. 10

9. In an electrical contact device, the com-

bination with a supporting member having bearings and means for holding conductors, 15 of reversible mechanism comprising a contact member and separable bearings adapted for engaging said bearings first named and clamping said conductors, and means for pressing said mechanism in opposite directions in its reversed positions. 20

In testimony whereof we have hereunto set our names this 13th day of November, 1918.

HENRY G. LEWIS.
WALTER S. MAYER.
